AUTOMATIC PACKING MACHINE

Valley V. Peone, Spokane, Wash.

Application February 24, 1948, Serial No. 10,471

11 Claims. (Cl. 226—25)

1

My present invention relates to machines or power operated appliances for successively filling portable receptacles with a predetermined bulk or weight of fluent material and more specifically to an improved automatic packing machine employing a hopper or feeding funnel with electrically operated feeding mechanism, together with feed controlling movements of the bag or other container being filled. While the machine is adapted for use with various fluent materials it is especially designed for use with flour as hereinafter described, and while I have utilized an electric motor and its controls for feeding the flour, and compressed air for automatically controlling parts of the machine or appliance, it will be understood that power other than electric power and fluid pressure other than compressed air may be employed in operating and controlling the machine.

In the operation of packing the flour in bags or sacks the bag is manually placed in position for filling and this manually operated movement of the bag is utilized in controlling pneumatic means for activating a vertically movable piston-driven positioning table for supporting the bag while it is being filled; and compressed air is employed for automatically stopping and cutting off the feeding mechanism when a predetermined optimum bulk or weight of the flour has been deposited in the bag. Means are also employed for automatically ejecting or displacing the filled bag from its supporting table, and for conveying the filled bag to a station where the bag is closed.

The invention consists in certain novel features of construction and combinations and arrangements of parts as will hereinafter be described and more particularly set forth in the appended claims.

In the accompanying drawings I have illustrated a complete example of a physical embodiment of my invention wherein the parts are combined and arranged in accordance with one mode I have thus far devised for the practical application of the principles of my invention. It will however be understood that changes and alterations are contemplated and may be made in these exemplifying drawings and mechanical structures, within the scope of my claims, without departing from the principles of the invention.

Figure 1 is a front view in elevation showing a flour packing machine in which my invention is physically embodied.

Figure 2 is a perspective view of a portion of the machine disclosing the switch-controlling

2

mechanism for the electric motor, and some of the compressed-air controls together with the automatically operated master valve for the fluid pressure.

5 Figure 3 is a horizontal sectional detail view taken on a horizontal plane just above the table and ejector cylinder and looking down.

Figure 4, Figure 5, and Figure 6, show respectively the master valve in draining position; in position to sustain the gradually lowering supporting table; and in position for raising or lifting the table to operative position.

Figure 7 is a longitudinal vertical sectional view of the pneumatic control for measuring or 15 weighing the filled bag.

Figure 8 is an enlarged view of the control valve mechanism for the ejecting means.

Figure 9 is a horizontal sectional view at line 9—9 of Figure 8; and

10 Figure 10 is a vertical sectional view of the ejection control valve of Fig. 8.

In carrying out my invention I employ a suitable frame here shown as consisting of two upright posts 1, 1, having a cross head from which 25 is suspended and supported a funnel shaped hopper 2 that is supplied with flour from a suitable source through the supply pipe 3, and the feed spout 4 of the hopper is equipped with an interior helical or spiral conveyor 5. The conveyor is operated for a positive and controlled feed of flour through the spout of the funnel with power 30 from an electric motor 6 mounted at the top of the main frame, and a chain drive 7 drives the vertically mounted conveyor shaft 8 to feed the flour from the lower end of the spout of the funnel shaped hopper.

An empty bag (not shown) is manually slipped up around the feed spout 4 until its interior bottom contacts the lower edge of the spout, and 35 then a vertically reciprocable horizontally disposed table 9 is automatically raised under fluid pressure until it contacts the bottom of the bag and supports the bag.

The upward movement of the table is accomplished by air pressure beneath a piston 10 located in a cylinder 11 mounted upon a floor or other suitable support, and the piston, which has an open center or port, is provided with a tubular rod 12 opening through the port into the bottom 40 of the cylinder, and with the upper end of the piston rod firmly attached to the underside of the table.

45 Admission of air under pressure to the cylinder and the tubular piston rod is controlled by the operator who strikes the cross head 13a lo-

cated in the path of the upper edge of the bag, and carried by angular lever 13 which is pivoted at 14 on the inner side of one of the posts 1. An arm of the angular lever depends along the outside of the post and its lower end terminates in a head 15 that is adapted to contact and contact with a valve arm 16 of a three way master control compressed air valve 17 mounted in upright position adjacent the post.

Air under pressure from a suitable compressor is supplied through pipe and port 18 to the valve 17, and a pressure pipe 19 from the valve extends to and is connected with the lower end of the cylinder 11 beneath piston 10.

As best seen in Fig. 6 the master valve is provided with an interior port 20, which, when the valve is turned by co-action of the head 15 and the valve arm 16, connects the supply and pressure pipes for conveying the fluid pressure to the interior of the cylinder and its tubular piston rod 12.

To limit and stop the upward movement of the table under air pressure, and to sustain the uplifted table, the port 20 is closed by turning the valve from position of Fig. 6 to position of Fig. 5, and this movement of the master valve is accomplished by movement of the table which is equipped with an angular adjustable stop-arm 21 attached, as by welding to the metallic table top, and the upturned end of the stop arm has a spring pressed pawl 22 mounted thereon beneath and in line with the valve arm 16. As the upwardly moving table nears the end of its movement, the pawl contacts with the arm, and the latter is swung to turn the valve to cut off the supply of compressed air, thus retaining the pressure within the cylinder and tubular piston rod.

As thus described it will be apparent that the vertically reciprocable table may be lifted, by the described air-motor, in position for supporting and sustaining the bag that has been applied to the spout of the funnel-shaped hopper, and the stop mechanism automatically cuts off the fluid pressure from the supply source, leaving the uplifted table in sustained position. Means are provided for reducing or relieving the sustaining air pressure in order that the table may be depressed by the compression of the flour in the container by the spiral conveyor 5 and also the weight of flour that is loaded in the bag, as will be described.

Simultaneously with this cutting off of the supply of compressed air to the master valve, the electric motor 6 is energized to drive the helical conveyor 5 and feed the flour into the waiting bag.

A conventional motor control switch for the electric motor is enclosed within a casing 27 mounted on an exterior face of one of the posts 1, and this switch is closed to energize the motor by movement of the table as it reaches its upward initial position for reception of the flour fed from the funnel. For this purpose a switch-control actuating arm 23 of angular shape is adjustably mounted on an upright frame 24 that is mounted as by welding on the table 9, and the horizontal portion of the angular arm terminates at the outer side of the post in a slide collar 25 with an upright pendant arm 26 of the casing 27. The upper end of the suspended arm 26 is operatively connected with the electric switch in the casing 27, and a spring 28 is coiled about the depending switch arm and interposed between a fixed

collar 29 and the casing or box 27. As the table reaches the end of its upward movement the slide collar 25 contacts with the fixed collar 29 to lift the switch arm 26 and close the switch for energizing the feed motor.

For retaining the switch in closed position and energizing the motor until the bag has been filled with flour to an optimum weight or quantity, a spring pressed detent 30 is mounted in and projected from a casing 31 attached to the post 1, and the detent is in position to engage a notch 32 on the lower end of the switch arm, thereby latching the switch in closed position.

As the fluent flour is fed into the bag, the accumulating weight of the load on the table and the compression by conveyor 5 depresses the table while an auxiliary reducing or relieving air valve 33, opening through the casting of the master valve to an enlarged port 34, gradually reduces the pressure in the cylinder 11 and the tubular piston rod 12; the port 28 being closed, and a drain port D of the master valve also being closed, as indicated in Fig. 5.

The pressure reducing valve 33 is adjustable by means of a screw 35 threaded in the casting of the valve, and a tension spring 36 (Fig. 4) bearing on the valve may be adjusted to permit reduction of air pressure and allow the table with the bag of flour to descend to a predetermined point. Should the feed of flour cease for any reason, the descent of the table and bag is stopped thereby equalizing the air pressure in the cylinder to a degree lower than the tension of the reducing valve, and the latter is automatically closed against further escape of compressed air from the cylinder, leaving the table and bag in stationary position.

In such an emergency, when the feed of flour is resumed and thereby increasing the weight on the table, the table gradually descends causing an increased air pressure that opens the reducing valve against the predetermined set of its tension spring for escape of air under pressure from the cylinder.

When an optimum predetermined quantity or weight of flour, ten pounds for instance, has been fed into the bag, the loaded package and the table create a pressure within the cylinder greater than that created by the feeding pressure of the conveyor 5, and at this time a weighing or metering mechanism (Fig. 7) is automatically activated.

The activation of this fluid pressure metering mechanism is instrumental in opening the control switch 27 of the electric motor 6; the motor is stopped, transmission of power to the conveyor 5 ceases, and the feed of flour through the discharge spout is cut off. Simultaneously or directly thereafter, the master control valve 17 is turned to draining position in Fig. 4 where air pressure may be drained through the exhaust or drain port D from the valve, and the master valve is closed against admission of air from the compressor.

The fluid pressure operated metering appliance, as seen in Fig. 7 includes a compressed air servo-motor having a double conical casing 37 which is connected by a threaded nipple 38 to the tubular piston rod 12 directly beneath the table 9, and the tubular piston rod opens through its piston 10 into the lower end of the cylinder 11. A transversely arranged diaphragm 39 is mounted in the vented casing and equipped with

a laterally extending plunger rod 40 having a plunger 41 reciprocable in its cylinder 42, a spring 43 being provided for retracting the diaphragm and the plunger. A reduced extension 44 of the cylinder 42 forms a housing for a longitudinally reciprocable and headed bar 45 that is equipped at its outer free end with a cam head 46.

In Figs. 1 and 2, where the electric motor is operating, the servo-motor 37 under air pressure has projected the detent, depressor, or cam-head 46, and the latter by frictional engagement with a foot or lug 47 of a slide bolt 48 has depressed and is holding down the spring lifted bolt. The spring lifted slide bolt 48 is equipped with a compression spring 49 and mounted in upright position in bearings 50 of an upright guide bracket or rod 51 attached to the inner side of one of the posts 1. A spring retracted pawl 52 is mounted in an adjustable housing 53 that is fixed by set screw 54 in set position, on, and travels with the spring bolt 48, and the pawl is located in position so that when lowered with the bolt it will contact an arm 55 of the master valve. The valve is thus turned to position in Fig. 4 where the supply is cut off, and pressure from the cylinder and tubular piston rod is drained through drain valve D.

Simultaneously with this turning movement of the master valve, a third arm 56 of the master valve lever, strikes against and retracts the pawl or detent 30 from the notched end 32 of the suspended switch control arm 28, and then the spring 28 depresses arm 26 to open the switch in casing 27 thereby deenergizing the motor 6; the motor having a standard type of brake that is instrumental in stopping the flour feeding mechanism.

Now, with the master valve in position of Fig. 4 and compressed air draining from the cylinder and tubular piston rod through the drain D of the master valve, the table with its package descends to the position of Fig. 1, and the filled bag is in position to be pushed horizontally, or ejected from the table, and carried or conveyed to the next station for closing and completing the package.

The horizontally disposed ejecting mechanism, as seen in Fig. 3 includes a compressed air servo-motor having a semi-circular ejecting head or pusher 57 conforming to the shape of the package and adapted to be projected across and over the table top for pushing the package therefrom. The ejector head 57 is mounted on the exterior end of an ejecting rod 58 extending into the cylinder 59 of the motor, and the rod is provided with an interior piston 60 as shown by dotted lines.

The reciprocating movement of the ejector is guided by means of a pair of exterior guide rods 61 and 62, attached at their front ends to the ejector head 57, and these rods slide in bearings 63 mounted on the exterior of the cylinder.

The admission of compressed air to and exhaust of air from the motor-cylinder is automatically regulated and controlled by an ejector valve 81 of the rotary type which is mounted by pin 82 and spring 83 in a cylindrical casing 64, interposed in the compressed air system of the machine adjacent the ejector-motor. The valve is provided with a compressed air supply pipe 65, and two alternate pressure and exhaust pipes as 66 leading to the front end of the motor cylinder, and pipe 67 leading to the rear end of the cylinder, at opposite sides of the piston 60.

The operation of the ejector-motor is governed through the rotary adjustment of the valve 81, and the valve is adjusted or actuated by the final descending movement of the table 9 (Fig. 8) as it contacts with a bell crank lever 68 pivoted at 69 in a stationary bracket 70.

The bell crank 68 is pivotally connected, by a reciprocable link 71, to the rotary valve lever or arm 72 that is fastened on the upper exterior end of the valve stem 82, and the oscillating movement of the bell crank is thus translated into rotary adjustment of the valve.

Due to the descending movement of the table 9 the valve 81 is turned to the position of Figs. 9 and 10, and compressed air from the supply pipe 65 is thus admitted to the interior of the valve casing above the valve; and from the interior of the casing the fluid pressure is extended through two aligned ports 73 and 74, and thence through pipe 67 into the rear end of the ejector cylinder behind the piston 66. Under this fluid pressure against the piston the ejector 57 is projected and the bag of flour is pushed across and from the table 9. As the ejector is projected, air from the front end of the motor cylinder is exhausted through pipe 66 to the port 75 of the valve casing into an exhaust chamber 76 of the valve, and then out through the central exhaust port 77 of the valve casing.

For retracting or withdrawing the ejector under fluid pressure after its working stroke, control means are employed including a pawl 78 mounted at the rear end of one of the guide rods, as 62, in position to contact the valve lever 72 at the end of the working stroke. Thus the valve 81 is turned counterclockwise in Fig. 9 to disconnect intake port 73 from the casing port 74, and chamber 76 from casing port 75; and at the same time to connect port 79 of the valve with port 75 of the casing and valve port 80 with port 74 and its chamber 84 with the drain port 77 of the casing.

In this position of the valve, air pressure is applied in the front end of the cylinder against the piston, to restore the ejector to position for another pushing operation, and the cylinder is exhausted from its rear end.

In Fig. 1 a portion of a horizontally disposed conveyor or endless belt 85 is illustrated as passing around a roller 86 journaled in bearings of a support or upright 84; and the belt is in position to receive the ejected package from the table and convey the package to a desired destination.

Having thus fully described my invention, what I claim as new and desire to secure by Letters Patent is:

1. In an automatic packing machine having a feeding funnel adapted to receive a manually fitted container, the combination with a fluid pressure operated motor, and a vertically reciprocable table aligned with the feeding funnel and operated by the motor, of a master-valve controlling the motor, a valve-operating arm, and means movable with the table for co-action with said arm for stopping the upward movement of the table.

2. In an automatic packing machine having a feeding funnel adapted to receive a manually fitted container, the combination with a fluid pressure motor, and a vertically reciprocable table operated by the motor and aligned with the funnel, of a master-valve controlling the motor and a valve arm, manually operated means co-acting with said arm to start lifting action of the motor, and means carried by the table and co-acting

with said arm to locate the table in sustaining position for the container.

3. In an automatic packing machine having a feeding funnel adapted to receive a manually fitted container, the combination with a fluid pressure motor, and a vertically movable table lifted by the motor and alined with the funnel, of a master valve and valve arm controlling the motor, a manually operated table-starting lever for co-action with said arm, and means cooperating with said arm for stopping the upwardly moving table in sustaining position for the container.

4. In an automatic packing machine having a feeding funnel adapted to receive a manually fitted container, a feed-conveyor in the funnel, and a motor for operating the feed-conveyor, the combination with a fluid pressure motor, and a vertically reciprocable table operated by the fluid pressure motor and alined with the funnel, of a master valve having an operating arm and controlling the fluid pressure motor, manually actuated means co-acting with said arm for starting lifting action of the fluid pressure motor to locate the table in sustaining position for the container, and means carried by the table for starting the feed-motor.

5. In an automatic packing machine having a feed funnel adapted to receive a manually fitted container, a conveyor in the funnel, an electric motor for the conveyor, and a control switch for the motor, of a fluid pressure motor and a table adapted to be lifted thereby in line with the funnel, a master valve having an arm and controlling the fluid pressure motor, a table starting lever located in the path of the fitted container for coaction with said arm, means actuated by upward movement of the table for co-action with said arm in stopping its movement, and means activated by upward movement of the table for closing the switch.

6. In an automatic packing machine having a feed funnel adapted to receive a manually fitted container, a conveyor in the funnel, an electric motor having a brake for the conveyor, and a control switch for the motor, of a fluid pressure motor and a table adapted to be lifted thereby in line with the funnel, a master valve having an arm and controlling the fluid pressure motor, a table-starting lever in the path of the fitted container for co-action with the arm, a resiliently retained bolt carried by the table for coaction with the arm in stopping the lift of the table, and means movable with the table for closing the switch.

7. In an automatic packing machine having a feed funnel adapted to receive a manually fitted container, a conveyor in the funnel, an electric motor for the conveyor, and a control switch for the motor, of a fluid pressure motor and a table adapted to be lifted thereby in line with the funnel, a master valve having an arm and controlling the fluid pressure motor, a table-starting lever in the path of the fitted container for co-action with said arm, a resiliently retained bolt movable with the table for co-action with the arm in stopping the lift of the table, a resiliently depressed switch-closing arm, and a bracket arm mounted on the table in position to coact with and lift the switch closing arm.

8. In an automatic packing machine having a

feed funnel adapted to receive a manually fitted container, an electric motor having a control switch, a feed conveyor in the funnel operated by the motor, and a compressed air system including a master valve, the combination with an air motor alined with the funnel and operated by said motor, of a vertically reciprocable table operated by the air motor, table-starting means in the path of the fitted container co-acting with the master valve, table-stopping means movable with the table for coaction with the master valve, and switch-closing means actuated by the upward movement of the table for starting the feed motor.

9. In a measuring mechanism for an automatic packing machine including a support and an upright bracket thereon, and having a pneumatic operating system, the combination with a pressure cylinder, a piston and a tubular piston rod open to the interior of the cylinder, and a weight-depressible table mounted on the piston, of a pneumatic master valve having a control arm, a resiliently mounted slide bolt mounted on the bracket for co-action with said arm in releasing pressure from the cylinder, a pneumatic servo-motor mounted on and communicating with the tubular piston rod, and a retractile de-pressor actuated by the servo-motor for coaction with the slide bolt.

10. In an automatic packing machine, the combination with an elevated funnel having a rotary feed conveyor, an electric motor operating the conveyor, and a closed control switch for the motor, of a pneumatic cylinder having a piston and piston rod alined with the funnel, a weight-depressible air-sustained table mounted on the piston rod, pneumatic operating means for withdrawing sustaining air pressure from the cylinder below the piston, and mechanical resiliently operated means for opening the switch.

11. In a pneumatically controlled system for an automatic packing machine including a weight-depressible, pressure-elevated and sustained table for supporting a container, the combination with a rotary three-way master valve having an outlet port and a spaced drain port, and resiliently controlled means for closing said outlet port, of means for operating the valve to lift the table, means for operating the valve to release pressure from the sustained table, and means for operating the valve for draining pressure from the table.
